The ornamental design for a golf article holder, as shown and described.

DESCRIPTION

FIG. 1 is a perspective view of a new design for a golf article holder that has a main peg member;

FIG. 2 is a right thereof;

FIG. 3 is a left view thereof;

FIG. 4 is a rear view thereof;

FIG. 5 is a front view thereof;

FIG. 6 is a top thereof;

FIG. 7 is a bottom view thereof;

FIG. 8 is a perspective view of a of a second embodiment of a golf article holder that includes an environmental peg member;

FIG. 9 is a right view of FIG. 8; and,

FIG. 10 is a left view of FIG. 8.

The broken lines shown in the drawings depict portions of the golf article holder that form no part of the claimed design.

1 Claim, 10 Drawing Sheets(56)
